RELISH TRAY

William D. Warren, 36 Sutton Place S., New York, N.Y.

Filed Feb. 13, 1961, Ser. No. 63,920

Term of patent 14 years

(Cl. D44—10)

FIG. 1

FIG. 2

FIG. 3

FIG. 4

FIG. 5

FIG. 1 is a front perspective view of a relish tray embodying my new design;

FIG. 2 is a top elevational view thereof;

FIG. 3 is a bottom view of the relish tray;

FIG. 4 is a side view thereof; and

FIG. 5 is an end view thereof.

I claim:

The ornamental design for a relish tray, as shown.
